(57) **CLAIM**

The ornamental design for an adjustable bed, as shown and described.

DESCRIPTION

FIG. 1 is a top perspective view of an adjustable bed, showing our new design in a first configuration of use;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the adjustable bed, shown in a second configuration of use; and,

FIG. 10 is an enlarged view of the selected portion 10 in FIG. 1.

The broken lines shown in the drawings depict portions of the adjustable bed that form no part of the claimed design.

1 Claim, 10 Drawing Sheets
